UNITED STATES PATENT OFFICE

2,510,615

ELECTRIC SPACE HEATER

William W. Wittie, Chicago, Ill.

Application August 15, 1949, Serial No. 110,306

3 Claims. (Cl. 219—39)

1

The present invention relates to portable electric space heaters, and more particularly to portable electric space heaters of the type using both radiation and convection to distribute the heat.

In the case of portable electric space heaters of the radiation type, there has been encountered the hazard of fire starting when inflammable material is placed close to such heaters. Not infrequently articles are hung up to dry before a radiant type of heater. The concentrated beam of heat energy may cause the articles to burst into flame when they have been dried because they were placed too close to the heater. Often-times space heaters of this type may also be placed too close to draperies and upholstered furniture so as to constitute a hazard.

Accordingly, it has been found preferable to employ an air circulating means in conjunction with portable space heaters to reduce the hazard encountered by other types of heaters and to provide a better distribution of heat. The mere provision of an air circulating means or fan for an electric heater, however, may be found to be rather inefficient from the standpoint of current consumption, because not infrequently the fan is so located or positioned as to merely create a turbulence of air within the heater housing.

Therefore, in accordance with the present invention, it is proposed to provide an improved construction for electric space heaters of the combination radiation and convection type which will consume a minimum of current for the circulation of heated air. By means of a particular construction set forth in detail in this application, it is possible to provide an efficient heater, irrespective of the ornamental appearance of the outer casing of the heater.

It is therefore an object of the present invention to provide an improved circulating air heater of the electric type.

Another object of the present invention is to provide an improved electric space heater which obviates the danger of concentrated heat liable to cause overheating and fires.

A still further object of the present invention is to provide an improved electric space heater of the circulating air type where an efficient fan of minimum size can be employed for economy in construction and operation.

Still another object of the present invention is to provide an improved electric space heater construction which will produce more efficient operation irrespective of the external design or appearance of the heater.

2

Other and further objects of the present invention subsequently will become apparent by reference to the following description taken in conjunction with the accompanying drawing 5 wherein:

Figure 1 is a front view of the essential elements of an electric space heater embodying the principles of the present invention;

Figure 2 is a fragmentary detail view showing 10 the construction of certain elements of the guide vanes of the heater shown in Figure 1;

Figure 3 is a fragmentary detail view showing 15 the construction of certain other elements of the guide vanes of the heater of Figure 1;

Figure 4 is a fragmentary detail view showing 20 the central construction of the guide vanes;

Figure 5 is a perspective view of the device 25 shown in Figure 1; and

Figure 6 is a fragmentary view of the center of 30 a guide vane embodying certain variations of construction as compared to that illustrated in Figure 1.

Referring to the drawing it will be noted that the essential elements of an electric space heater 25 are supported by a relatively horizontal cylinder 11 which may be provided with suitable support brackets or feet 12. Extending up from the rear of the cylinder 11 are a pair of brackets 13 which support an electric motor 14 which carries 35 a fan 15. The fan 15 is located within the cylinder 11 in the proximity of the rear of the cylindrical housing.

The cylinder 11 is provided with a plurality 35 of spaced apertures 16 for receiving a plurality of insulators 17 which extend inwardly into the cylinder 11 to provide insulated supports for an electric heating element 18. Adjacent the bottom of the cylinder 11, suitable apertures 19 are provided for insulated studs 21 which carry binding posts 22. The inner extremity of the binding posts 22 serve to support the extremities of the electric heating element 18. The lower extremities of the binding posts 22 receive the conductors for the electric motor 14 and the conductors 40 which lead to an electric switch and the cord which is arranged to be plugged into a suitable electric outlet.

For economy in construction and for providing the maximum energy transfer from the heating 50 element, it has been found preferable to provide an open coil heating element 18 which at suitable intervals engages notches 23 in the insulating support 17. Thus the heating element 18 is arranged in a generally polygonal form or in a 55 generally circular manner along the periphery

of a co-axial circle of smaller diameter than the diameter of the drum 11.

By placing the fan 15 within the cylinder or drum 11 there is obviated to a considerable extent the probability that the fan would waste considerable energy by merely creating a turbulence of air within the outer casing of the electric space heater. In order to further assure maximum efficiency of the fan 15, there is provided adjacent the front edge of the drum or cylinder 11 a guide vane structure which divides the axial area of the drum 11 into at least eight equal segments. It has been found that a smaller number of segments will not produce as great an efficiency as at least eight segments. For simplicity in manufacture, it has been found convenient to form the vane structure of two members 24 and 25 consisting of metal strips arranged at right angles to each other in the manner illustrated in detail in the fragmentary view of Figure 2. The ends of the strips 24 and 25 are bent at right angles as at 26 on the strip 24, and these ends are then fastened to the inner surface of the cylinder or drum 11, preferably by spot welding. The guide vane structure is completed by two other strips 27 and 28, each extending to the center of the drum 11 for engagement by the strip 25. Each of the strips 27 and 28 is bent at right angles at its center and is provided with a notch 29. The ends of the strips 27 and 28 are provided with suitable right angled portions which in turn are secured or spot-welded to the inner surface of the cylindrical drum 11.

From Figures 2, 3 and 4 it will be seen that two similar strips 27 and 28 are provided with notches 29 extending half-way through strips 27 and 28. The strip 24 has a notch 31 which extends half-way through that strip. The strip 25 has a notch 32 of sufficient dimensions to accommodate all of the strips 24, 27 and 28 in the manner shown in detail in the fragmentary view of Figure 4. Thus a relatively simple interlocking structure is obtained. The axial dimensions of the various strips for the proper efficiency has been found to be of the order of one-eighth to one-sixth of the diameter of the cylinder 11. If the strips 24, 25, 27 and 28 are made any narrower, the efficiency of the guide vane structure drops off appreciably. The guide vane structure serves to prevent packing or channelling of the air so as to assure proper absorption of the heat from all of the electrical heating element 18. Thus the arrangement produces a column of heated air at a minimum operating cost.

If, desired, the vane structure illustrated in Figure 1 may be modified in accordance with the structure illustrated in Figure 6. This arrangement includes a notched circular or cylindrical strip 33 located a short distance from the center. In such construction shown in Figure 6, it, of course, will be evident that each of the strips 24, 25, 27 and 28 are suitably provided with cooperating notches so as to provide the necessary interlock with the circular or cylindrical member 33.

While for the purpose of illustrating and describing the present invention a preferred embodiment has been illustrated in the drawing, it is to be understood that such variations in the

construction and in the arrangement of the components is contemplated as may be commensurate with the spirit and scope of the invention set forth in the accompanying claims.

What I desire to protect by U. S. Letters Patent is claimed as follows:

1. A portable electric space heater comprising a short horizontal metal cylinder provided with a supporting stand, an axially mounted fan located at the back end of said cylinder, a plurality of spaced apertures in said cylinder, an insulating support mounted in each aperture, an open coil electric heating element arranged within said cylinder in polygonal form on said insulators, 10 a guide vane grille positioned adjacent the front of said cylinder, said guide vane including two metal strips diametrically perpendicular to each other and two metal strips each bent into a right angle and positioned to bisect the angles formed by said first two strips.

2. A portable electric space heater comprising a short horizontal metal cylinder provided with a supporting stand, an axially mounted fan located at the back end of said cylinder; a plurality of spaced apertures in said cylinder, an insulating support mounted in each aperture, an open coil electric heating element arranged within said cylinder in polygonal form on said insulators, 15 a guide vane grille positioned adjacent the front of said cylinder, said guide vane including two metal strips diametrically perpendicular to each other and two metal strips each bent into a right angle and positioned to bisect the angles formed by said first two strips.

3. A portable electric space heater comprising a short horizontal metal cylinder, an axially mounted fan at the back end of said cylinder, an open coil electric heating element arranged within said cylinder in a generally circular manner, a guide vane structure arranged flush to the front end of said cylinder and including two metal strips arranged diametrically perpendicular to each other and two metal strips each bent into a right angle and positioned to bisect the angles formed by said first two strips, each strip having an axial dimension of the order of one-eighth of the diameter of said cylinder, 35 three of said strips having centrally located notches on one edge, the other strip having a centrally located notch on the opposite edge whereby to engage said first notches to interlock all of said strips at their centers.

WM. W. WITTIE.
